W. E. WINE.

DOOR CONSTRUCTION.

APPLICATION FILED MAY 21, 1920. RENEWED SEPT. 1, 1921.

1,410,539.

Patented Mar. 21, 1922.

UNITED STATES PATENT OFFICE.

WILLIAM E. WINE, OF TOLEDO, OHIO.

DOOR CONSTRUCTION.

1,410,539.

Specification of Letters Patent. Patented Mar. 21, 1922.

Application filed May 21, 1920, Serial No. 383,037. Renewed September 1, 1921. Serial No. 497,656.

To all whom it may concern:

Be it known that WILLIAM E. WINE, a citizen of the United States, residing at Toledo, in the county of Lucas and State of Ohio, has invented certain new and useful Improvements in Door Constructions, of which the following is a specification.

My invention relates to a new and useful improvement in door constructions and has 10 for an object to provide a door that will be exceptionally strong, relatively light and exceedingly simple in construction.

Another object of my invention is to provide a door construction that although relatively light in weight, will be far stronger than a wooden one of the same size, or a wooden one that is reinforced with iron bands as is often the practice to-day.

My door is especially adapted for use on 20 freight cars where an exceedingly strong door is necessary, although it can advantageously be used on any other structure, calling for a strong door.

Wooden doors at the present time are expensive to construct, relatively heavy and will not withstand for any great length of 25 time the heavy service that they encounter when used on freight cars, as besides the normal heavy uses they are often damaged 30 by operators forcing them open with bars or other members if for any reason they become momentarily stuck.

Metal doors as heretofore constructed, on the other hand, are formed from large heavy 35 metal sheets which in turn make a heavy door and necessitates heavy and expensive machinery to bend or cut them to shape.

Another object therefore of my invention is to overcome the above enumerated objections and form a door that is novel in construction, quickly and readily assembled and relatively light in weight.

In the drawings, showing a preferred form 45 of my invention,

Fig. 1 is a front view of my improved door construction,

Fig. 2 is an edge view thereof,

Fig. 3 is a sectional view taken on line 3—3 of Fig. 1, and looking in the direction 50 of the arrows,

Fig. 4 is a fragmentary perspective of one of the channel members used in the door construction,

Fig. 5 is a gusset or reinforcing member

as shown in the blank and before being bent 55 to its final shape, and

Fig. 6 is a side view of the same and in its final form.

Referring now to the drawings, it will be seen that the door comprises and is made up 60 of a plurality of channel sections 1 which are adjacently placed as clearly shown in Fig. 1.

The length of the sections, of course, depends on the desired height of the door, and 65 any multiple of sections may be used depending on the width desired for the door.

Channel sections are made up in standards of different widths and it will be understood that if multiples of say the size shown do 70 not make in the aggregate the desired width, sections of a greater or lesser width would be used.

The flanges 2 of each channel section are further bent to form the relatively small inwardly extending flanges 3.

After the proper number of sections of the desired width are placed in position an angle iron 4 is placed along their upper ends so that its webs 5 will abut against all of the 80 ends of the sections, and the flange 6 of the angle iron will extend across the face or web of each of the sections 1.

Each section is then riveted to the flange 6 of the angle iron 4, thus tightly holding 85 each and all of the sections in their set and desired position.

A second angle iron 7 is likewise riveted to each and every section at their lower ends to thus completely reinforce the upper and 90 lower ends of the door, and all sections then spot welded.

To further strengthen the door and to provide against the diagonal strains, a plurality of members 8 in the form of gussets are 95 used, which gussets may be formed from blanks as clearly shown in Fig. 5. These gussets are triangular in shape and are provided with flanges 9 and 10 that may be first drilled for rivets as at 11 and may then be 100 bent. One is then placed in each corner of the door as clearly shown in Fig. 1.

In Fig. 3 is shown the manner in which they are applied, the flange 9 being securely riveted to the web 5 of the angle iron and 105 the flange 10 being likewise riveted to the flange 2 of the channel section. It is also to be carefully noticed that one edge of the

body portion of the gusset extends under one small flange 3 of the channel section and tightly bearing against the same while the opposite end of the gusset will extend beneath the opposite small flange 3 of the same section.

By placing these gussets as above mentioned the door is greatly strengthened, each corner being box-like in cross-section, therefore 10 by providing as strong a structure as is possible to obtain with the amount of metal used.

Of course these gussets may be made larger than shown in the drawing if desired and additional ones may be used along the upper and lower ends of the door if ever 15 found necessary.

In Fig. 1 I have shown a plurality of holes 12 through which hangers (not shown) may 20 be bolted, while near one edge of the door I have shown openings 13 through which a hasp may be secured.

When used on freight cars it will be desirable to place the door so that the smooth 25 surface is presented to the inner surface of the car, but on the other hand when used in other places either side may be used for the inner or outer side.

From the foregoing it will be seen that 30 I have provided a door construction which will be relatively light in weight, may be of any width or height; it being necessary simply to use channels, the multiples of which give the desired width, and the manner of 35 assembling is such that no great length of time will be necessary in riveting the sections to the upper and lower angles which act as girders to which the strains and stresses are directed by the channels. Furthermore, 40 by providing gussets as shown they having their body portion away from the inner side of the channel and fitting snugly beneath the small flanges a very rigid and strong construction is obtained.

Having thus described my invention, what 45 I claim as new and desire to secure by Letters Patent is:—

1. A door construction comprising a plurality of channel sections, each of said sec-

tions having its flanges bent inwardly to 50 form further flanges, an angle iron extending transversely of the upper ends of each section and one of its faces riveted to the faces of said sections and its other face forming the upper edge of the door, a second 55 angle member likewise secured at the lower ends of the sections to form the bottom of said door, reinforcing members at the four corners of said door, the body portion of said reinforcing member in each instance 60 tightly fitting beneath the aforementioned inwardly extending flanges and each reinforcing member being bolted to a flange of the channel section and to a face of the transversely extending angle member. 65

2. A door construction comprising a multiple of channel sections, each section having inwardly disposed flanges, an angle iron extending transversely of all of said 70 sections and riveted to the face of each of said sections and the other face of said angle member forming the top surface of the door, a similar angle iron secured to the lower ends of each of said sections and likewise forming the bottom of the door, gusset 75 members disposed in each corner of said door and snugly fitting beneath the adjacent inwardly extending flanges of the channel sections and the body portion of said gusset so disposed to form each corner of the door 80 box-like in cross-section.

3. A door comprising a plurality of channel sections disposed lengthwise of each other, an angle iron having one face thereof riveted to each of said sections and the 85 other face of said angle iron forming the upper edge of said door, a second angle iron having one face riveted to the faces of said channel sections at their lower ends and the other face of said angle iron forming the 90 bottom of said door, reinforcing means secured at each corner of said door, the outer flanges of the two opposite outer sections forming the outer sides of the door.

In testimony whereof I affix my signature.

WILLIAM E. WINE.
